UNITED STATES PATENT OFFICE.

JOHN F. MILLER, OF TRAIL, BRITISH COLUMBIA, CANADA, ASSIGNOR OF
ONE-HALF TO WALTER H. ALDRIDGE, OF TRAIL, BRITISH COLUM-
BIA, CANADA.

APPARATUS FOR CASTING METAL SHEETS.

No. 857,885.

Specification of Letters Patent.

Patented June 25, 1907.

Application filed May 24, 1906. Serial No. 261,923.

To all whom it may concern:

Be it known that I, JOHN F. MILLER, a citizen of the United States, residing at Trail, in the Province of British Columbia, 5 Dominion of Canada, have invented certain new and useful Improvements in Apparatus for Casting Metal Sheets, of which the following is a specification, reference being had to the drawing accompanying and forming 10 part of the same.

My invention relates to devices for forming sheets or plates of metal, for use as cathode "starting sheets" in electrolytic refining of base bullion, for electrodes in storage batteries, and in general for any purpose for 15 which such sheets or plates may be used.

The chief object of my invention is to provide an apparatus by which uniform, dense sheets may be cast, in a rapid and efficient 20 manner.

In carrying out my invention in its preferred form, I employ an inclined casting or rectangular form, provided at its sides with upstanding lips or flanges to confine the 25 table, consisting of a plane surface of square molten metal to the bed or table. At the higher end of the table is a pivoted ladle, extending preferably across the entire width of the table, so arranged that it may be tilted 30 and its contents thereby discharged upon the table. When thus discharged, the molten metal flows down over the table and solidifies thereon, thus forming the desired sheet, which may then be removed and given further treatment, if any be needed, to prepare 35 it for the purpose intended.

The preferred embodiment of the invention, which consists in the novel features, combinations of elements, and arrangement 40 of parts hereinafter described and more particularly set forth in the claims, is shown in the accompanying drawings, in which

Figure 1 is a plan view of the apparatus, and Fig. 2 a side elevation.

45 The casting table or bed is indicated by A. This member, in the preferred form of the invention, is of rectangular form as shown, and is provided at each side with a flange, as indicated at B and C. It is supported in an inclined position by four legs, D, E, F and G, suitably braced if desired. At the higher end of the table is a ladle H,

hinged or pivoted to the table, as shown, by means of hinges I. The form of the ladle is immaterial, but it should be of such shape as 55 to permit the metal to run freely out when the ladle is raised to the vertical position. The pivots on which it swings are so arranged as to keep the edge of the ladle close to or preferably slightly overhanging the 60 edge of the table. A handle J may be provided for manipulating the trough or ladle.

The operation of the apparatus may be briefly described as follows: A quantity of molten metal, as for example lead, sufficient 65 to form the plate is tapped into or otherwise deposited in the trough and the latter then quickly raised to the position shown in dotted lines in Fig. 2; whereupon the metal runs out upon the table, (in a transversely un- 70 broken stream and not in a number of narrow streams, as might be the case if the metal were discharged through spouts or equivalent orifices), and runs down over the table, being confined thereto by the side 75 flanges. The relatively low temperature of the table and the exposure of the metal to the air over so large a surface causes solidification to take place rapidly. Assuming the 80 temperature of the bed and that of the molten metal to be constant, the thickness of the cast plate will depend upon the inclination of the table, which of course may be constructed to have any desired inclination. The angle of the table determines the rate of 85 flow of the metal over it, hence if nearly level the metal will flow slowly and will therefore solidify before it has had time to spread over a large area. On the other hand, if the table is steeper the metal will flow more quickly 90 and so be spread over a larger area before it has time to congeal. The inclination of the table being the same, the size of the plate will in general depend upon the quantity of metal deposited upon the table, as will be 95 readily understood.

Having now described my invention, what I claim is:

1. In an apparatus for casting lead sheets, the combination of a flat surface disposed at an inclination to a horizontal plane, and means at the upper edge of the surface for discharging an unbroken stream of molten material thereupon. 100

2. In an apparatus for casting lead sheets, the combination of a table having a plane surface disposed at an inclination to a horizontal plane, flanges at the sides of the table 5 projecting above the surface for confining the material under treatment and a ladle of the full width of the table hinged to the same at

the upper edge thereof for discharging an unbroken stream of molten material upon the inclined surface.

JOHN F. MILLER.

Correction in Letters Patent No. 857,885.

It is hereby certified that in Letters Patent No. 857,885, granted June 25, 1907, upon the application of John F. Miller, of Trail, British Columbia, Canada, for an improvement in "Apparatus for Casting Metal Sheets," an error appears in the printed specification requiring correction, as follows: Page 1, lines 23 and 25 should be transposed; and that the said Letters Patent should be read with this correction therein that the same may conform to the record of the case in the Patent Office.

Signed and sealed this 20th day of August, A. D., 1907.

[SEAL.]

C. C. BILLINGS,
Acting Commissioner of Patents.

2. In an apparatus for casting lead sheets, the combination of a table having a plane surface disposed at an inclination to a horizontal plane, flanges at the sides of the table 5 projecting above the surface for confining the material under treatment and a ladle of the full width of the table hinged to the same at

the upper edge thereof for discharging an unbroken stream of molten material upon the inclined surface.
